UNITED STATES PATENT OFFICE.

CALEB D. PAGE, OF MORGAN, COLORADO.

HOLDER FOR HITCHING-STRAPS.

SPECIFICATION forming part of Letters Patent No. 325,359, dated September 1, 1885.

Application filed December 19, 1884. (No model.)

To all whom it may concern:

Be it known that I, CALEB D. PAGE, of Morgan, Weld county, Colorado, have invented a new and useful Improvement in 5 Hitching-Strap Holders, to be attached to the saddle or any part of a harness or to a riding-saddle, of which the following is a specification and description, reference being had to the accompanying drawings.

10 Figure 1 is a perspective view of my improved hitching-strap holder. Fig. 2 is a longitudinal section of the same. Fig. 3 is a top view.

Similar letters refer to similar parts throughout the several views.

15 The object of this invention is to provide a device for holding the loose end of a hitching-strap when not in use, and to obviate the necessity of tying into the rings of the harness 20 or riding-saddle, thereby bungling it with loops and knots and necessitating considerable labor and annoyance in doing up and undoing; and it is intended as an improvement on my Patent No. 265,699, granted October 10, 1882, 25 and on Patent No. 275,695, granted me April 10, 1883.

In the drawings, A represents the base-plate, by which the device is secured to the harness or saddle, its length being about three 30 and a half inches, its width seven-eighths of an inch. J represents the upper jaw, provided on the lower side with the teeth T; L, the lower jaw, pivoted at P, and closed by the action of the coil pivotal spring S working in 35 the chamber, as shown, and giving the jaw a

strong upward pressure in the direction of the teeth T; G, the guard which protects the lower jaw, L, which prevents straps or garments from catching under it, and also prevents the jaw from striking the ends of the 40 teeth T.

It will be seen that from the form and dimensions of the base-plate it can be easily attached to any strap on the harness by means of rivets or screws, and when so attached the 45 hitch-strap can be readily put in place by pressing it against and sliding it along the jaw L under the teeth of the jaw J, where it is firmly held by the upward pressure of the jaw L against the toothed jaw J, and can 50 easily be removed by pressing against the jaw L and slipping it out from under the toothed jaw J.

Having thus described my invention, what I desire to claim and to secure by Letters Patent is—

1. In a strap-holding device, the plate A and rigid jaw J, in combination with the spring-actuated pivoted jaw L, limited by the guard G, all substantially as set forth. 60

2. In a strap holding device, the combination of the base A, provided with the guard G and the rigid toothed jaw J, with the pivoted jaw L, actuated by the coiled spring S, all arranged substantially as set forth, and for 65 the purposes described.

CALEB D. PAGE.
